UNITED STATES PATENT OFFICE.

MILTON L. SAMMONS, OF KANSAS CITY, MISSOURI.

CARBURETER MECHANISM.

1,072,875.

Specification of Letters Patent. Patented Sept. 9, 1913.

Application filed May 29, 1913. Serial No. 770,680.

To all whom it may concern:

Be it known that I, MILTON L. SAMMONS, a citizen of the United States, residing at Kansas City, in the county of Jackson and 5 State of Missouri, have invented a certain new and useful Improvement in Carbureter Mechanisms, of which the following is a specification.

My invention relates to improvements in 10 carbureter mechanisms.

It is particularly adapted for use in connection with carbureters of explosive engines employed for propelling automobiles.

Considerable difficulty is experienced in 15 the operation of explosive engines at high altitudes, due to the rarefied condition of the air and to lack of moisture in the air.

One of the objects of my invention is to provide a simple and efficient mechanism 20 for economically mixing water vapor with air prior to its introduction into the carbureting chamber of a carbureter, so as to increase the efficiency of the engine.

A further object of my invention is to 25 provide a simple, efficient and economical mechanism for heating the carbureting chamber of a carbureter, so as to increase its efficiency.

A further object of my invention is the 30 provision of novel mechanism for bringing into coöperative relationship with each other, the mechanism controlling the operation of the carbureter, and the mechanisms which convert water into vapor and steam 35 for respectively vaporizing the air used in the carbureter and for heating the carbureting chamber of the carbureter.

Other novel features of my invention are 40 hereinafter fully described and claimed.

In the accompanying drawings which 45 illustrate the preferred form of my invention—Figure 1 is a side elevation showing my improved mechanism applied to a six-cylinder explosive engine, some of the parts being broken away. Fig. 2 is a vertical sectional view on the line *a*—*b* of Fig. 1. Fig. 3 is a side elevation showing my invention applied to a six-cylinder engine, the view being taken at the opposite side of the 50 engine from that of Fig. 1. Fig. 4 is a vertical section on the line *c*—*d* of Fig. 2. Fig. 5 is a vertical section, enlarged on the line *e*—*f* of Fig. 2.

Similar reference characters designate 55 similar parts in the different views.

Referring particularly to Fig. 5, 1 designates the carbureting chamber of a carbureter, which is provided with an air inlet 2, with which connects a conductor 3, having its opposite end mounted in a hole 60 provided in the bottom of a horizontal tube 4, which encircles and is spaced apart from a manifold exhaust pipe 5, connected with the cylinders 6, of the explosive engine. The ends of the tube 4 are open to the atmosphere. The space between the tube 4 and the pipe 5 forms a chamber 7 for the commingling of air and water vapor.

For producing the vapor which is to be mixed with the air, there is provided above 70 the engine a water tank 8, with which is connected one end of a water conductor 9, which, at its other end, is provided with a horizontal portion, which is mounted in a longitudinal slot in the upper side of the 75 tube 4, and which is disposed parallel with the exhaust pipe 5, and is provided in its lower side with a plurality of openings 10 which discharge into the chamber 7 against the pipe 5 and through a wire screen 11, 80 which is of channel form and located longitudinally in the chamber 7.

Forming a part of the conductor 9, is a valve casing 12, in which is mounted a shut-off valve of the ordinary type and which is 85 provided with a crank arm 13, to which is connected one end of a rod 14, the other end of which is secured to a crank arm 15, which is secured to a horizontal rock shaft 16, pivotally mounted in bearings 17, which are 90 supported in any suitable manner, as by means of the central cylinder 6. The rock shaft 16 has secured to it a crank arm 18, the upper end of which is bifurcated and embraces a forwardly and rearwardly extending operating rod 19, which at one end is pivotally connected to a crank arm 20, which is secured to a pivot stem 21, of a butterfly valve 22, which is mounted in the carbureter chamber 1, and which controls 100 the discharge of the explosive mixture through the outlet 23 of said chamber. Two collars 24, are mounted on the rod 19, at opposite sides of the crank arm 18. The forward end of the rod 19, is connected to 105 one arm of a bell crank lever 25, the other arm of which is connected to the lower end of a rod 26, which has its upper end connected to a pedal 27.

Encircling the exhaust pipe 5 is a hollow 110

cylinder 28, having closed ends and forming, with the pipe 5, an annular chamber 29, with which communicates one end of a conductor 30, having its other end communicating with an annular chamber 31, which encircles the chamber 1, as shown in Fig. 5. Said annular chamber 31 is provided with an outlet 32.

Forming a part of the conductor 33, which is connected to the tank 8, and which has a horizontal portion located in a slot in the top of the cylinder 28, is a valve casing 34, provided with a shut-off valve having a crank arm 35, pivoted to one end of a rod 36, the other end of which is pivoted to a crank arm 37, which is secured to the rock shaft 16. The horizontal portion of the conductor 33 is provided in its lower side with discharge openings 38, disposed so as to discharge into the chamber 29 and against the exhaust pipe 5.

Communicating with the air inlet 2, as shown in Fig. 5, is a vertical air pipe 39, into which extends a pipe 40, which is connected with a liquid fuel tank, not shown.

The arrangement of the valves in the casings 12 and 34, and the valve 22, is such that when the pedal 27 is depressed and the rod 19 moved forwardly, the shaft 16 will be rocked so as to simultaneously open the valves in the casings 12 and 34, at the same time that the butterfly valve 22 is opened. A spring 41, may be provided to retract the bell crank lever 25, and through it the rod 19, so as to close the butterfly valve 22, and the valves within the casings 12 and 34, by the mechanism already described.

When the valves 12 and 34 are opened, the water will pass from the tank 8, through the conductors 9 and 33 respectively, and into the chambers 7 and 29. The water entering the chamber 7, will pass through the screen 11, which will serve to diffuse the water over the pipe 5, the heat from which will vaporize the water which in this form will mix with the air entering at the end of tube 4, the mixed air and vapor passing from the chamber 7 by way of the conductor 3, into and through the inlet 2 and pipe 39. The mixture will intermingle with the liquid fuel which is discharged from the pipe 40. The presence of the water vapor will increase the efficiency of the explosive mixture. The water passing through the conductor 33 will be converted into steam in the chamber 29, due to the heat of the pipe 5, and passing from said chamber into the annular chamber 31, through the conductor 30, will heat the chamber 1, thereby adding to the efficiency of the explosive mixture.

It will be noted that when the butterfly valve 22 is closed no water will pass from the tank 8 through the conductors 9 and 33, and when the butterfly valve is partly opened the valves in the casings 12 and 34

will be partly opened. Thus the amount of water which is discharged from the tank 8 through the conductors 9 and 33, will be proportionate to the amount of fuel burned, and when the carbureter is not in operation no water will pass from the tank 8.

I do not limit my invention to the structure described and illustrated, as modifications, within the scope of the appended claims, may be made without departing from the spirit of my invention.

Having thus described my invention, what I claim and desire to secure by Letters Patent is:—

1. In a carbureter mechanism, a carbureter having a carbureting chamber provided with an air inlet, an exhaust pipe, means by which the heat from the exhaust pipe converts water into vapor, means by which the heat from the exhaust pipe converts water into steam, means by which the steam so produced is employed to heat the carbureting chamber of the carbureter, and means by which the vapor produced from the water is mixed with air and the mixture carried to and discharged through said inlet into the carbureting chamber.

2. In a carbureter mechanism, a carbureter having a carbureting chamber provided with an air inlet, an annular chamber encircling the carbureting chamber and provided with an outlet, an exhaust pipe, a water tank, two annular chambers encircling the exhaust pipe, one of said annular chambers having an inlet for air, two conductors respectively connecting the annular chambers which encircle the exhaust pipe with said air inlet and the annular chamber which encircles the carbureting chamber.

3. In a carbureter mechanism, a carbureter having a carbureting chamber having an air inlet and provided with an outlet, a valve controlling said outlet, a chamber having an inlet for air, means for heating the last named chamber by exhaust from the engine, a water conductor discharging into said last named chamber and arranged so that the heat of the exhaust gases converts the water discharged from said conductor into vapor which mixes with the air in said last named chamber, a valve controlling said conductor, a conductor connecting said last named chamber with said air inlet of said carbureting chamber, and means for simultaneously operating said valves.

4. In a carbureter mechanism, a carbureter having a carbureting chamber provided with an air inlet and an outlet, a valve controlling said outlet, an exhaust pipe, a chamber encircling said exhaust pipe and having an opening for admitting air, a water conductor discharging into the last named chamber and against said exhaust pipe, a valve controlling said conductor, a con-

ductor connecting said last named chamber with said air inlet, and means for simultaneously operating said valves.

5. In a carbureter mechanism, a carbureter having a carbureting chamber provided with an air inlet, an exhaust pipe, an annular chamber encircling said exhaust pipe and provided with an opening for admitting air, a water conductor discharging 10 into said annular chamber and against said exhaust pipe, and a conductor connecting said annular chamber with said air inlet.

6. In a carbureter mechanism, a carbureter having a carbureting chamber provided with an air inlet, an exhaust pipe, an annular chamber encircling said exhaust pipe and provided with an opening for admitting air, a water conductor discharging 15 into said annular chamber, a valve for controlling said conductor, and a conductor connecting said annular chamber with said air inlet.

7. In a carbureter mechanism, a carbureter having a carbureting chamber, an exhaust pipe, an annular chamber encircling said exhaust pipe, a water conductor discharging 20 into said annular chamber, an annular chamber encircling said carbureting chamber, and a conductor connecting said 30 annular chambers.

8. In a carbureter mechanism, a carbureter having a carbureting chamber provided with an air inlet and an outlet, a valve controlling said outlet, an exhaust 35 pipe, an annular chamber encircling said exhaust pipe, a water conductor discharging into said annular chamber, a valve controlling said water conductor, an annular chamber encircling said carbureting 40 chamber and provided with an outlet, a conductor connecting said annular chambers, and means for simultaneously operating said valves.

9. In a carbureter mechanism, a carbureter having a carbureting chamber provided with an air inlet and an outlet, a valve controlling said outlet, an exhaust pipe, two annular chambers encircling said exhaust pipe, two conductors respectively 45 discharging into said annular chambers, one of said annular chambers having an

opening for admitting air, two valves controlling said conductors respectively, an annular chamber encircling said carbureting chamber and having an outlet, two conductors respectively connecting said first named annular chambers with said air inlet and the last named annular chamber, and means for simultaneously operating 55 said valves.

10. In a carbureter mechanism, a carbureting chamber having an air inlet, means by which heat derived from the exhaust of an engine is employed to convert water into vapor, means for mixing the vapor thus 60 produced with air, means for carrying the mixed vapor and air to and through said inlet, means by which heat derived from the exhaust of an engine converts water into steam, and means by which the steam 65 thus produced is employed to heat said carbureting chamber.

11. In a carbureter mechanism, an exhaust pipe, a tube encircling and spaced apart from said exhaust pipe and having 70 one end open to the atmosphere, a water conductor disposed parallel with said exhaust pipe and having an opening discharging into the space between said tube and said pipe, a carbureting chamber having an 75 air inlet, and a conductor connecting with said air inlet and with the space between said tube and said pipe.

12. In a carbureter mechanism, an exhaust pipe, a tube spaced apart from and 80 encircling the exhaust pipe and provided with an air inlet and having a longitudinal slot in its upper side, a water conductor mounted in said slot parallel with said pipe and provided in its lower side with an 85 opening discharging into said tube, a carbureting chamber having an air inlet, and a conductor connecting with said air inlet and with the space between said tube and said exhaust pipe.

In testimony whereof I have signed my name to this specification in presence of two subscribing witnesses.
